Attorney

UNITED STATES PATENT OFFICE.

WILLIAM C. HUNTOON, JR., OF EAST GREENWICH, RHODE ISLAND.

COLLAPSIBLE TUBE.

Application filed November 10, 1923. Serial No. 673,933.

To all whom it may concern:

Be it known that I, WILLIAM C. HUNTOON, Jr., a citizen of the United States, residing at East Greenwich, in the county of Kent 5 and State of Rhode Island, have invented new and useful Improvements in Collapsible Tubes, of which the following is a specification.

This invention relates to certain new and 10 useful improvements in collapsible tubes and the primary object thereof is to provide a tube with improved means for ejecting the contents in the form of a ribbon and without removal of the usual closing cap.

15 A further object of the invention is to provide novel means for sealing or closing the outlet.

The invention also aims to provide a simple and economical structure and has still 20 further and other objects which will be later set forth and of themselves manifested in the course of the following description.

In the drawings:—

Figure 1, is a top plan view of the invention; 25

Figure 2, is a section on line 2—2 of Figure 1; the body of the tube being shown in fragment;

30 Figure 3, is a bottom plan view of the cap and

Figure 4, is a bottom plan view of a modified form of the cap.

In proceeding in accordance with the present invention, the body 1 of the tube 35 is of the usual collapsible type and has an exteriorly threaded neck 2. The threads however terminate in spaced relation to or are omitted at the inner or base end of the neck leaving a smooth or plain portion indicated at 3.

The outer or free end of the neck is formed with an inwardly bevelled or tapered seat 4 which inclines inwardly toward the interior of the neck.

45 A cap 5 is threaded over the neck and is provided with an inwardly extending enlargement or portion 6 the periphery of which is bevelled or tapered at 7 to form a face which conformably engages the 50 bevelled seat 4.

The cap is provided with an elongated outlet slot 8 which extends through its outer face and from which extends a pair of opposed arcuate or segmental slots 9, the latter being divergently related and extending downwardly through the bevelled face 7 of the cap between the upper and lower portions of said face. The curved slots 9 are thus seen to merge into the single outlet slot 8. 55

The lower or inner end of the cap is provided with an attenuated flange 10, the latter being spun to extend inwardly into the space 3 and to thus engage beneath the threads of the neck, preventing entire removal of the cap. 60

In the modified form of the invention depicted in Figure 4 of the drawings, the curved slots 9 are supplanted by straight flared slots 12 extending from small openings 12', the structure otherwise being the same as that shown and described in the preferred form. 70

In operation, the cap is turned to free the slots 9 or 12 of the seat 4 whereupon the tube is collapsed, causing the contents to egress through the slots 9 or 12 and thence outwardly in ribbon form through the single outlet slot 8. 75

Having thus described my invention, what I claim as new and desired to secure by Letters Patent is:—

1. A collapsible tube having a neck formed with an inwardly tapering seat, and a cap on the neck having a diametrical discharge slot, said cap having an enlarged part formed with a pair of divergent openings each leading from the discharge slot through the adjacent bottom portion of the cap, the enlarged part being peripherally tapered to engage on said seat so as to cause the latter to close the lower ends of the divergent openings. 85

2. A collapsible tube having a neck formed with a circular seat, and a cap on the neck having a diametrical discharge slot and having an enlarged part formed with a pair of openings each leading from the discharge slot through the bottom portion of the cap, said bottom portion of the cap 90

100

being formed to engage on said seat so as to cause the latter to close the lower ends of the openings.

3. In combination with a collapsible tube having a neck with a flared discharge orifice providing a valve seat on the free end edge of the neck, and a cap threaded on the nozzle and provided with a downwardly facing conical valve for engaging the seat, 10 said cap having a discharge opening branch-

In testimony whereof I have signed my name to this specification in the presence of two subscribing witnesses.

WILLIAM C. HUNTOON, JR.
